UNITED STATES PATENT OFFICE.

BENJAMIN W. JACOBS, OF CHICAGO, ILLINOIS.

NAIL-FILE.

SPECIFICATION forming part of Letters Patent No. 569,285, dated October 13, 1896.

Application filed February 15, 1896. Serial No. 579,335. (No model.)

To all whom it may concern:

Be it known that I, BENJAMIN W. JACOBS, a citizen of the United States, and a resident of Chicago, in the county of Cook and State 5 of Illinois, have invented certain new and useful Improvements in Nail-Files, of which the following is a specification, reference being had to the accompanying drawings, forming a part thereof, in which similar letters of 10 reference indicate corresponding parts.

This invention relates to nail files, cutters, and cleaners; and the object thereof is to provide an improved device of this class which is simple in form and construction and which 15 possesses many advantages over devices of this class now in use.

The invention is fully disclosed in the following specification, of which the accompanying drawings form a part, in which—

20 Figure 1 is a side view of my improved nail-file; Fig. 2, a section thereof on the line 2 2; Fig. 3, a side view of a modified form of construction; Fig. 4, a section thereof on the line 4 4; and Figs. 5 and 6 are sections similar to 25 that of Fig. 4, but showing different forms of construction.

In the practice of my invention I provide a nail file, cutter, and cleaner which comprises a handle A and a blade B, and the 30 blade B is provided with an end section b, which is pointed and preferably sharpened on both sides, and the body of the blade B is formed into a file, as shown at b², and formed in one edge thereof are segmental or semi- 35 circular notches or recesses b³, which extend about half-way through the blade, thus leaving a straight edge b⁴, which is also provided with a file-surface, and the notches or recesses, or the inner walls thereof, are inclined and 40 also preferably provided with file-surfaces a. These notches or recesses are longer at one end than the other, as clearly shown in Fig. 1, the object of this formation being to adapt them to nails of different fingers, some of 45 which are smaller than others, and the operation of this device will be readily understood from the foregoing description when taken in connection with the accompanying drawings.

50 In the construction shown in Fig. 3 the

straight edge b⁴ is cut out in forming the segmental notches or recesses b³, and the back walls of said notches or recesses are inclined or beveled, as shown at b⁵, and three different forms of this construction are shown in 55 Figs. 4, 5, and 6, and in Fig. 6 an outwardly-directed projecting flange or shoulder b⁶ is provided, which extends over the inner portion of the segmental notch or recess, and this shoulder or projection is also segmental 60 in form.

By means of these various forms of construction almost any style or shape of finger-nail may be easily and perfectly trimmed in any desired manner, and it will thus be seen 65 that I provide an effective device and one which is comparatively inexpensive, while being well adapted to accomplish the result for which it is intended.

Having fully described my invention, I 70 claim as new and desire to secure by Letters Patent—

1. As an improved article of manufacture, a nail-file, provided with a blade having a file-surface, one edge of the blade being cut away 75 to form a series of segmental notches or recesses, which are also provided with file-surfaces, substantially as herein shown and described.

2. The herein-described nail-file constructed with a blade provided with a file-surface, and having one edge thereof cut away to form a series of segmental recesses or notches b³ which are reduced in size from the point of the blade toward the opposite 85 end thereof, said blade being provided with a straight edge or web b⁴ below said recesses, also provided with file-surfaces, whereby the nail is made uniformly convex and is smoothed on the under surface, substantially as and 90 for the purpose described.

In testimony that I claim the foregoing as my invention I have signed my name, in presence of the subscribing witnesses, this 14th day of February, 1896.

BENJAMIN W. JACOBS.
